UNITED STATES PATENT OFFICE.

JOHN TRUBISKY, OF KIPLING, OHIO.

VEGETABLE SLICER.

Application filed March 14, 1923. Serial No. 625,013.

To all whom it may concern:

Be it known that I, JOHN TRUBISKY, a citizen of United States of America, residing at Kipling, county of Guernsey, and State of Ohio, have invented certain new and useful Improvements in Vegetable Slicers, of which the following is a specification.

This invention relates to improvements in slicers, particularly vegetable slicers, and it is the principal object of my invention to provide a slicer in which the article to be sliced is continuously and progressively pressed against the slicing tools.

A further object of the invention is the provision of a slicer comprising a plurality of slicing tools allowing an adjustment and locking in their adjusted positions.

A still further object of the invention is the provision of a slicer of this character which may be cheaply, yet durably constructed and attached to a suitable support and which allows a ready removal of the sliced material.

These and other objects of my invention will become more fully apparent as the description thereof proceeds, and will then be specifically pointed out in the appended claim.

In the accompanying drawing:

Figure 1 is a side view of a vegetable slicer constructed according to the present invention.

Figure 2 is a front view thereof.

Figure 3 is a top plan view of the slicer.

Figure 4 is a cross-section through the slicer on line 4-4 of Figure 1.

Figure 5 is a top plan view of the knife disc.

Figure 6 is a section through the same on line 6-6 of Figure 7.

Figure 7 is an edge view of the knife disc.

A casing 10 is divided by a partition wall 11 into a rear chamber 12 and a cylindrical front chamber 13.

A lid 14 for the front chamber is hinged as at 15 to the roof 16 of the rear chamber, and a peg 17 has its head 18 shouldered to rest upon cover 14, while its shank extends into the casing or chamber 13 and carries within the same, at its lower end, a pressure plate 19, while a strong spiral spring 20 is wound around the shank of peg 17 and tends normally to press plate 19 down into engagement with a head of cabbage resting on knife disc 21.

The disc 21 is provided with a plurality

of obliquely disposed openings 22 permitting the passage of the knives or slicing tools 23, each having an upper bevelled end 24, and a lower angular arm 25 provided with a threaded perforation through which a screw bolt 26 is guided, which is also passed through one end of a bracket 27, secured with its other end to the underside of disc 21 as at 28. One end of bolt 26 carries a head 29, while its other end is guided in a ring socket 30 on tool 23 so as to allow an adjustment and exchange of the slicing tools.

The chamber 13 is made accessible from the front by a door 31 hingedly secured to the casing at 32, at its lower end, while movable cleats 33 allow a clamping of its upper end against the outer wall of chamber 13 in order to keep the door closed.

The slicer is supported by runners 34 or the like to keep it spaced from a support in which a shaft 35 is journaled, which projects at one end over the runner 34 and carries a crank 36 by means of which the shaft can be rotated.

Intermediate its ends, shaft 35 carries a bevel gear 37 in mesh with a bevel gear 38 at the lower end of a vertical stub shaft 39 which carries the knife disc 21.

Angle irons 40 are attached with one arm to the outer faces of the runners 34 and through their other arms fastening screws 41 are passed, by means of which the slicer can be clamped to a table or other suitable support.

The operation will be perfectly clear from the above description, after the slicer has been clamped to a support by means of clamps 41, a head of cabbage or other article to be sliced is brought into chamber 13 through door 31 and the same is closed by the proper operation of the cleats 33. The head of cabbage rests between disc 21 and plate 19 and will be pressed by the spring 20 against the knives. When now crank 36 is rotated, the knives will slice the article and the slices may be removed through openings 42 and 43 in the walls of chambers 12 and 13, or may be removed through the rear of chamber 12 as the rear part of the partition 11 does not reach entirely down to the bottom of the casing.

Having thus described my invention what I claim as new and desire to secure by Letters Patent is:

A slicer comprising a rotatable disc, a plurality of inclined openings in said disc, a

plurality of knives in said openings, each of said knives having a lower perforated shoulder, an intermediary ring and an upper cutting edge, brackets secured to the under-
5 side of said discs having perforated arms, and screw bolts passed through said perforated arms and the perforated shoulder and

ring for allowing an adjustment of the cutting edges to project more or less above the upper face of said disc, and means for rotating said disc. 10

In testimony whereof I have affixed my signature.

JOHN TRUBISKY.
